US00D567780S

(12) **United States Design Patent** (10) **Patent No.:** **US D567,780 S**
Kim et al. (45) **Date of Patent:** **** Apr. 29, 2008**

(54) **MOBILE PHONE**

(75) Inventors: **Young-Sae Kim**, Los Altos, CA (US);
Chi-Young Ahn, Seoul (KR);
Young-Ju Yeo, Seoul (KR);
Chang-Hwan Hwang, Goyang-si (KR)

(73) Assignee: **Samsung Electronics Co., Ltd.**,
Suwon-Si (KR)

(**) Term: **14 Years**

(21) Appl. No.: **29/254,289**

(22) Filed: **Feb. 22, 2006**

(30) **Foreign Application Priority Data**

Nov. 18, 2005 (KR) 30-2005-0038971

(51) **LOC (8) Cl.** **14-03**

(52) **U.S. Cl.** **D14/138**

(58) **Field of Classification Search** D14/496,
D14/138, 341-347; 455/575.3, 575.1; D21/517,
D21/329, 333
